UNITED STATES PATENT OFFICE.

ALBERT F. DAVIS, OF RUTLAND, VERMONT.

DESIGN FOR A GRINDING-DISK FOR MILLS.

SPECIFICATION forming part of Design No. 32,220, dated February 13, 1900.

Application filed December 27, 1899. Serial No. 741,768. Term of patent 14 years.

To all whom it may concern:

Be it known that I, ALBERT F. DAVIS, a citizen of the United States, residing at Rutland, in the county of Rutland, State of Vermont, have invented and produced a certain new and original Design for a Grinding-Disk for Mills, of which the following is a specification, reference being had therein to the accompanying drawings, in which—

10 Figure 1 is a plan view of a grinding-disk for mills, showing my design; and Fig. 2 is a vertical cross-section through the same on the line 2 2 of Fig. 1.

As shown in the drawings, the leading or 15 material feature of my design consists of a series of wedge-shaped ribs of different lengths disposed radially to the center of the disk and having their bases toward said center.

As shown in Fig. 1, the periphery of the 20 disk is of curved outline, as at A, and extending inward therefrom is a series of short ribs B, while intermediate of these ribs there is a radially-disposed series of ribs C, extending inward to a greater distance than the ribs 25 B. At intervals around the periphery of the

disk is located a series of wedge-shaped ribs D, extending inward to a greater distance than either the ribs B or C and disposed radially to the center of the disk. At the center of the disk an aperture A' of circular form 30 is shown, and from the periphery of this aperture to the outer edge of the disk extends a series of ribs E of wedge shape and radially disposed at intervals between the before-mentioned ribs. All of these ribs are provided 35 with sides inclining toward each other, thus providing wedge-shaped figures with their bases toward the center of the disk and their apices extending to the periphery thereof.

Having described my invention, what I 40 claim is—

The design for a grinding-disk for mills, substantially as shown and described.

In testimony whereof I affix my signature in presence of two witnesses.

A. F. DAVIS.
